UNITED STATES PATENT OFFICE.

RALPH F. CHRISTIAN, OF CHICAGO, ILLINOIS.

CASKET HANDLE.

1,420,815.

Specification of Letters Patent. Patented June 27, 1922.

Application filed December 8, 1919, Serial No. 343,237. Renewed May 8, 1922. Serial No. 559,453.

To all whom it may concern:

Be it known that I, RALPH F. CHRISTIAN, a citizen of the United States, and a resident of the city of Chicago, county of Cook, 5 and State of Illinois, have invented certain new and useful Improvements in Casket Handles, of which the following is a specification.

My invention relates to new and useful 10 improvements in casket handles, and has for its object the provision of a casket handle which will be simple in structure, economic of manufacture, and highly efficient in use.

Another object is the provision in a casket 15 handle of means for securing the handle to the escutcheon plate, whereby the points of pivotal connection are relieved from strain when the handle is used.

Other objects will appear hereinafter. 20 The invention consists in the combinations and arrangements of parts hereinafter described and claimed.

The invention will be best understood by reference to the accompanying drawings 25 forming a part of this specification, and in which,

Fig. 1 is a plan view of my invention,

Fig. 2 is a central vertical sectional view of my invention,

30 Fig. 3 is a fragmentary sectional view showing the means of mounting in my invention, and

Fig. 4 is a fragmentary plan view of the inner side of my invention.

35 The approved form of construction comprises an escutcheon plate 5 provided with openings 6 by means of which the plate is to be fastened to the casket. Formed in the plate 5 is a tongue 7 which is substantially semi-circular. Extending around the periphery of the tongue 7 and formed in the plate 5 is a slot 8, the slot 8 thereby being substantially semi-circular or of horse shoe shape. Formed in the member 5 are openings 10 which are separated from the ends of the slot 8 by means of a portion 9 of the member 5. As shown in Fig. 4, the members 9 are formed by punching the openings 10 in the plate 5. The openings 10, however, 40 may be connected with the adjacent end of the slot 8 by a slot extending between the openings 10 and the adjacent end of the slot 8 in which case the members 9 will form gudgeons serving to interrupt the slot 8 adjacent its lower ends. Used with the member 5 is a hanger arm 11 which is provided

with a knuckle 12 at its lower end, in which the handle 13 is secured. The upper end of the member 11 is formed trough-shaped and is laterally turned to form an elbow portion 60 14. Provided upon the member 11 adjacent its upper end is a shoulder 15 which is adapted, when the hanger bar 11 is in use, to abut against the plate 5 and thereby limit the upward swinging of the hanger bar 65 relatively to the plate. As shown in Fig. 2, the sides of the trough-shaped portion of the hanger bar 11 are extended at the ends to form a projecting portion 17. Formed upon the member 11 adjacent its upper end, at opposite sides thereof, are tongues 16.

In assembling the hanger bar upon the escutcheon plate the tongues 16 are inserted in the opening 10 and the tongue 7 is engaged in the trough-shaped portion of the 75 member 11 adjacent the upper end thereof. In this manner the hanger bar 11 is pivotally mounted upon the gudgeons and upon the upward swinging of the member 11 relatively to the plate 5, the tongues 16 80 engage against the plate 5 and are bent upwardly toward the member 17, so as to assume the position shown in Fig. 3, thereby securely locking the hanger bar in position upon the plate. As clearly seen in Fig. 85 2, the body of the plate 5 is forced outwardly, so as to lie in a different plane from its contour line. Upon the upward swinging of the member 11 relatively to the plate, the shoulder 15 contacts with the 90 plate 5, the trough-shaped portion or the upper end of the member 11 passes into the outwardly recessed portion of the member 5 through the slot 8. After the shoulder 15 has come into contact with the plate 5 95 a further upward swinging of the member 11 is resisted by the shoulder 15. In order to move the member 11 upwardly further, the shoulder 15 would force the plate 5 inwardly and thereby the plate 5 would force 100 the pivotally mounted end of the member 11 downwardly so that the weight of the casket would be transmitted to the gudgeons 9. Ordinarily the plate 5 would resist the strain transmitted through the hanger bar 105 11, but in the case of transmitting the weight of the casket to the gudgeons 9, the same would be unable to withstand the strain with the result that the hanger bar would be wrested out of its mounted position, owing to the fact that the gudgeons 9 are of a comparatively small size. To 110

relieve the member 5 of the strain exerted upon it at the point where the member 15 contacts, the tongue 7 is provided. At the same time that the member 15 contacts with 5 the member 5, the rim of the tongue 7 is closely engaged by the inner surface of the hanger bar 11. Therefore, should the member 5 be pressed inwardly so as to force the mounted end of the member 11 downwardly, 10 the member 7 prevents its downward movement at its point of connection, thereby preventing the member 5 from being pressed inwardly. With this construction, the gudgeons 9 serve only to retain the 15 hanger bar 11 in its mounted position and are never subjected to any of the strain incidental to the lifting of the casket.

While I have illustrated and described the preferred form of construction for carrying my invention into effect, this is 20 capable of variation and modification without departing from the spirit of the invention. I, therefore, do not wish to be limited to the precise details of the construction 25 set forth, but desire to avail myself of such variations and modifications as come within the scope of the appended claims.

Having described my invention, what I 30 claim as new and desire to secure by Letters Patent is:

1. A casket handle comprising an escutcheon plate; a hanger bar pivotally mounted on said plate, said bar being formed trough-shaped at its upper end; 35 and means on said plate for engaging in said end of said bar for limiting its upward

swinging, said means comprising a tongue punched out of said plate and adapted to engage the inner surface of said end of said bar forming a limiting stop for said 40 bar, substantially as described.

2. A casket handle comprising an escutcheon plate; a tongue formed in said plate, said plate having a slot extending around said tongue; a hanger bar; an elbow 45 formed on said hanger bar projectable inwardly through the slot formed in said plate, and adapted to contact with the rim portion of the tongue on said plate to limit upward movement of said bar.

3. A casket handle comprising an escutcheon plate; a tongue formed in said plate, said plate having a slot extending around said tongue; a hanger bar; an elbow formed on said hanger bar, adapted to project inwardly through the slot formed in said plate 55 and to bear against the tongue on said plate when said bar is raised to operative position, and a shoulder formed on said bar adapted to abut against said plate above 60 said slot for limiting the upward swinging of said bar, the elbow and shoulder on said bar constituting the limiting stop members of said bar.

In testimony whereof I have signed my 65 name to this specification in the presence of two subscribing witnesses.

RALPH F. CHRISTIAN.
